UNITED STATES PATENT OFFICE

92,522

DESIGN FOR A UTILITY HOLDER FOR SEAMSTRESSES

Howard T. Chinn, Atascadero, Calif.

Application May 1, 1933, Serial No. 47,949

Term of patent 3½ years

To all whom it may concern:

Be it known that I, HOWARD T. CHINN, a citizen of the United States, residing at Atascadero, in the county of San Luis Obispo, and State of California, have invented a new, original, and ornamental Design for a Utility Holder for Seamstresses, of which the following is a specification, reference being had to the accompanying drawing, forming part thereof.

What is claimed is:

The ornamental design for a utility holder for seamstresses, as shown.

HOWARD T. CHINN.
